Letters Patent No. 22, dated Feb. 26, 1861.
Whole No. 1387.

The schedule referred to in these Letters Patent and making part of the same.

To all whom it may concern:

Be it known that I, Sampson Hainemann, of New York, in the County and State of New York, have invented or produced a new and original design for a Trade Mark, for Paint, and I do hereby declare that the following is a full and exact description of the same reference being had to the accompanying drawing.

My invention is composed of lines and characters delineating the goddess of Justice in connection with the following words, to wit: Magnesid Green.

My figure of Justice has a sketchy base as shown by A. a skirt of wavy and nearly parallel lines as shown by B, and C. a horizontal belt as shown by D. a right arm strongly delineated hanging by her side, as shown by E, a sword grasped in her right hand hanging perpendicularly nearly to the ground as shown by F. a right shoulder bare as shown by G. a chest very faintly outlined as shown by H. a left arm strongly delineated extending at an angle of about 30° descending, from the shoulder to the elbow, and ascending nearly perpendicularly from the elbow to the wrist as shown by I, a left hand bent inward toward the head at an angle of about 150° as shown by J, features of the face faintly delineated the eyes being obscurely shown, as shown by K, and the whole is surmounted by hair plainly dressed and parted in the centre as shown by L.

The supports of the scales are strongly shown and descend to the level of the chin of the figure as shown by M, the beam of the scales is light ly shown as denoted by N, the cords or chains from the ends of the beam to the several scales are lightly but distinctly represented as shown by O, and the two scales themselves are very strongly shown one concealing a large portion of the breast of the figure as shown by P.

The words "Magnesia Green" are made to surmount the figure, the word "Permanent" to underlie or extend across below the base of the figure, and the remaining words are arranged below the word Permanent in the manner plainly shown in the drawing.

The effect of the whole is to produce a symmetrical and tasty, and at the same time a novel and distinctive mark by which I intend that a specific variety of paint shall be known and recognised in the trade. I intend by this mark both to ornament my packages, boxes, bags or the like, in which this paint is packed, and to distinguish it unmistakeably from all other kinds of paint, whether such other kinds be manufactured by myself and partner or by any other person or persons.

Having now fully described my mark, what I claim is the picture or figure to be used as a trade mark and designed as described, with the words "Magnesia Green" associated therewith as described.
